PNEUMATIC TIRE

Dale J. Beaudoin, Opelika, Ala., and William K. Pope,
Mount Clemens, Mich., assignors to Uniroyal, Inc.,
New York, N.Y.

Filed May 18, 1970, Ser. No. 23,030

Term of patent 14 years

Int. Cl. D12—15

U.S. Cl. D90—20

FIG. 1 is a perspective view of a pneumatic tire showing our new design, it being understood that the tread and buttress pattern of the detailed portion of the design is repeated throughout the circumference of the tire and that the shaded buttress pattern is repeated on the opposite side of the tire;

FIG. 2 is an enlarged, fragmentary plan view of the tread of FIG. 1;

FIG. 3 is an enlarged, fragmentary plan view of the buttress of FIG. 1;

FIG. 4 is a fragmentary sectional view of the tread, taken substantially on the plane indicated by line 4-4 of FIG. 2; and

FIG. 5 is a fragmentary sectional view of the buttress, taken substantially on the plane indicated by line 5-5 of FIG. 3.

The characteristic feature of our design resides in the tread and buttress pattern extending from one sidewall of the tire to the other and shaded in FIG. 1.

We claim:

The ornamental design for a pneumatic tire, substantially as shown and described.
